UNITED STATES PATENT OFFICE.

STEPHEN J. DICKHAUT, OF SAUGERTIES, NEW YORK, ASSIGNOR TO THE MARTIN CANTINE COMPANY, OF SAUGERTIES, NEW YORK, A CORPORATION OF NEW YORK.

PRINTER'S OVERLAY AND UNDERLAY BOARD AND PROCESS OF MAKING SAME.

1,324,038.

Specification of Letters Patent.

Patented Dec. 9, 1919.

No Drawing.

Application filed March 15, 1918. Serial No. 222,678.

To all whom it may concern:

Be it known that I, STEPHEN J. DICKHAUT, a citizen of the United States, and a resident of Saugerties, in the county of 5 Ulster and State of New York, have invented a certain new and useful Improvement in Printers' Overlay and Underlay Boards and Processes of Making Same, of which the following is a specification.

10 My improvement relates to printers' overlay and underlay boards and to processes of making them and the base for such boards, and processes of building up such base into suitable printing thickness. It has for its 15 object to improve and simplify such processes and to render them more accurate and reliable and to produce an improved overlay and underlay board and one more durable in subsequent printing operations and 20 more soft and flexible than heretofore possible. It consists of the novel processes and products herein described and claimed.

My invention is addressed generally to printers' overlay and underlay boards such 25 as are described in U. S. Letters Patent No. 892,166 of June 30th, 1908, to Lankes & Schwarzler. In making a base such as is described in said patent, difficulty has been encountered in producing a base that will 30 be stained or tinted only on its exterior surfaces and not inside, which latter would render the base useless for its purpose. Difficulty has also been encountered in making not only the base but also the finished board 35 soft and flexible so that it will not easily crack in use. My invention is addressed to removing these objections and also to making the finished board strong and durable and capable of withstanding stresses, blows 40 and pressure to which it is subjected in a press in subsequent printing operations.

I have discovered that suitable paper stock may be dipped into a staining or tinting solution and the latter solution stain or 45 tint only the thin exterior surfaces of the paper without penetrating its substance, if the solution is made sticky or non-penetrating by the inclusion of a proper sticky or adhesive material and that the base may be 50 made soft and flexible by introducing into the tinting solution a softening agent. Any suitable coloring material may be employed and any suitable sticky and softening agent

may be employed. I find the following formula gives good results, namely, a staining 55 solution containing in ten gallons of water one-fourth of an ounce of scarlet anilin, one ounce of glue, preferably hide glue, and one and a half gills of glycerin. The proportions may, of course, be varied to suit varying 60 constituents and conditions. I take any suitable paper, such as market rag stock paper of about 4 to 4½ points, and dip it into the solution. This tints or stains both faces. The excess pink solution is then squeezed 65 out between rollers. The hide glue prevents the staining solution from penetrating the interior of the white rag stock paper so that after the base has been built up with etchable material, printed upon and etched, the 70 pink stain will form a guide to the etcher to enable him to determine when to stop the etching operation. When the etcher notices the pink color appearing, he will etch still 75 farther but carefully and will stop when the pink color has been eliminated. This will bring the deeper etched parts of the board down to the original base and will enable a uniform thickness to be obtained through 80 the board. By my improvement a white base may be used and the building up layers of etchable material may also be white so as to furnish a good printing surface.

In the operation of building up a sheet of paper from the base of sufficient thickness to receive the imprint of the design for the board, I apply to the base one or more coatings of a building up solution containing etchable building material including a tough resistance substance adapted to render the board more durable and resistant to the blows and pressure incident to the printing operations in a press. The substance I have preferred to employ for this purpose is casein, although other similar substances 95 may be employed for the purpose. It is of a tough resistant nature and acts somewhat as a cushioning means to the printing surfaces of the overlay or underlay board.

I also preferably employ in the solution 100 for the coating a softening agent which is adapted to render the board soft and flexible in use, tending to prevent cracking, etc. I prefer to use for this purpose glycerin, although other substances of a similar nature 105 may be employed.

I also preferably use in the coating solution chalk and other etchable, hardening, polishing and binding materials.

Any suitable formula may be employed for the coating solution to build up the base to the desired thickness. I have found the following formula to give excellent results, namely, in 15 gallons of water, 41 lbs. calcium carbonate, 15 lbs. blanc fixe, 43 lbs. of clay, 26 lbs. satin white, 5½ lbs. casein, 10 oz. boro-phosphate, 1 oz. liquid ammonia, 1 pint glycerin and 10½ lbs. of glue, preferably hide glue. In the above formula, the clay serves to give body, the satin white to make the surface of the paper smooth and hard and firm, the blanc fixe to make the paper heavy and so that it will take ink better, hide glue as a binder, glycerin as a softening agent serving to make the board soft and flexible and casein as the tough resistant cushioning element.

It will be understood that some of the above ingredients may be omitted altogether or may be replaced by equivalent substances and that the proportions may be varied within reasonable limits to suit varying conditions.

By my improved method a simple means for making overlay and underlay boards is provided which enables the etcher to know exactly when to stop the etching operation and have a uniform and proper thickness to the board and the relief, and a board is produced which is soft and pliable and not liable to crack in use and which is resistant to the shocks of a printing press in actual operation and is very durable.

What I claim as new and desire to secure by Letters Patent is:

1. The process of making printers' overlay or underlay boards which consists in dipping the paper base into a staining solution adapted to stain only the surface of the base without penetrating its body and adapted to make the base soft and flexible, applying to the base thus tinted one or more coatings of a building up solution containing etchable building material adapted to make a good printing surface, including a tough resistant substance adapted to make the board more durable in use in the printing press and including a softening agent to render the board soft and flexible, printing upon the board and dipping the board 55 in the etching solution until the exterior tint of the base is seen and disappears.

2. The process of making printers' overlay or underlay boards which consists in dipping the paper base into a staining solution containing hide glue and glycerin, applying to the base thus tinted one or more coatings of a building up solution containing etchable building material adapted to make a good printing surface including casein and glycerin.

3. In the manufacture of a paper base upon which to build one or more coatings, capable of being subsequently etched away, to form a paper of sufficient thickness upon which to print a design for a printer's overlay or underlay board, the use of a staining solution containing a sticky or adhesive ingredient adapted to cause the solution to stain only the surface of the base and prevent it from penetrating the body of the base. 70

4. In the manufacture of a paper base upon which to build one or more coatings, capable of being subsequently etched away, to form a paper of sufficient thickness upon which to print a design for a printer's overlay or underlay board, the use of a staining solution containing hide glue adapted to cause the solution to stain only the surface of the base and prevent it from penetrating 80 the body of the base.

5. The process of making a paper base upon which to build one or more coatings, capable of being subsequently etched away, to form a paper of sufficient thickness upon 90 which to print a design for a printer's overlay or underlay board, which consists in making a soft and flexible paper base by adding to the other constituents of the base a softening agent adapted to keep the paper 95 base soft and flexible, and in dipping the paper base into a staining solution containing a sticky or adhesive ingredient adapted to cause the solution to stain only the surface of the base and prevent it from penetrating 100 the body of the base.

6. The process of making a paper base upon which to build one or more coatings, capable of being subsequently etched away, to form a paper of sufficient thickness upon 105 which to print a design for a printer's overlay or underlay board which includes the application to the base of a softening agent adapted to keep the paper base soft and flexible. 110

7. The process of making a paper base upon which to build one or more coatings, capable of being subsequently etched away, to form a paper of sufficient thickness upon which to print a design for a printer's overlay or underlay board, which includes the application to the base of glycerin. 115

8. The process of making a paper base upon which to build one or more coatings, capable of being subsequently etched away, to form a paper of sufficient thickness upon which to print a design for a printer's overlay or underlay board, which consists in dipping the paper base into a staining solution containing hide glue and glycerin. 120

9. In the manufacture of printers' overlay or underlay boards the process of building up a sheet of paper of sufficient thickness to receive the imprint of the design for such a board, which consists in applying to the 130

paper base one or more coatings of a building up solution containing etchable building material including a tough resistant substance adapted to make the overlay or underlay board more durable in use.

10. In the manufacture of printers' overlay or underlay boards the process of building up a sheet of paper of sufficient thickness to receive the imprint of the design for such a board, which consists in applying to the paper base one or more coatings of a building up solution containing etchable building material including casein.

11. In the manufacture of printers' overlay or underlay boards the process of building up a sheet of paper of sufficient thickness to receive the imprint of the design for such a board, which consists in applying to the paper base one or more coatings of a building up solution containing chalk and other etchable materials and casein and glycerin.

12. As an article of manufacture a printer's overlay or underlay board having a design printed in relief thereon with the relief portions of the board back of the printed design made up in part of tough resistant or cushioning material adapted to withstand the shocks and pressure of a printing press.

13. As an article of manufacture a printer's overlay or underlay board having a design printed in relief thereon with the relief portions of the board back of the printed design made up in part of casein.

14. As an article of manufacture a printer's overlay or underlay board having a design printed in relief thereon with the relief portions of the board back of the printed design made up in part of chalk and other filling material, a cushioning material and a softening agent.

In testimony whereof, I have signed my name to this specification.

STEPHEN J. DICKHAUT.
